Application January 27, 1942, Serial No. 428,420

9 Claims. (Cl. 244—77)

This invention relates in general to control devices and has as its primary object to provide an improved device for predetermining and automatically controlling the rate and direction of operation of the device and consequently the direction and rate of turn of an airplane controlled by an automatic pilot.

For flying an airplane by means of an automatic pilot and in connection with a directional gyro it is proposed to provide a double solenoid motor for energizing the rudder control means and a manual switch for selectively operating the left or right solenoid for an operation of the airplane rudder in the left or right direction for such turns as are desired. Thus, as long as the switch is manually maintained closed in either direction the turn of the airplane in the desired direction continues by means of the operation of the rudder. In addition to this regulation of rudder control of the airplane, it is proposed to automatically regulate the rate of turn in accordance with a manual setting of a timing apparatus in circuit with the solenoid motor. In this manner the turn continues at a predetermined rate as long as the solenoid switch is closed by the operator for effecting a turn in either direction.

With the foregoing and other objects in view, the invention resides in the combination of parts and details of construction hereinafter set forth in the following specification and appended claims, certain embodiments thereof being illustrated in the accompanying drawing, in which:

Figure 1 is an illustrative view in elevation of the solenoid motor, the circuit diagram and the timing mechanism, with the ratchet wheels being partly broken away to show their relationship to each other and their pawls and detent;

Figure 2 is a view of the solenoid motor and casing taken at right angles to that shown in Figure 1; and

Figure 3 is a view taken on the line 3—3 of Figure 2.

Referring more particularly to the drawing, the solenoid motor may comprise two solenoids 1 and 2 with armatures 3 and 4, respectively, protruding at their upper extremities and which are secured at their bases to the bracket 5. Two magnetic members 34 and 17 are fixed to a rocking frame 7 positioned on the stub shaft 6 which is journalled at one end in the upwardly extending arm of the supporting bracket 5. The other end of the shaft 6 is journalled in the bracket plate 5' thereby supporting the rocking frame and the pawls 8 and 9 pivoted at opposite ends

5 to the rocker frame. Pawl 8 is pivoted at 16 to the upright portion 11 of the frame 7 which has secured thereto the magnetic member 34 to engage armature 3, when the solenoid 1 is electrically energized against the action of a tension spring 18 secured to the tie bar 19 and to an extension 20 of the rocker frame 7. Pawl 9 is pivoted at 15 to the rocker frame 7 and carries a magnetic member 17 adapted to engage the armature 4 of the solenoid 2, when the latter is energized, against the action of a tension spring 12 secured to the spacer bar 13 and to an extension 14 of the rocker frame 7.

10 Also mounted in the housing on a rotatable stub shaft 21, in parallel relation to shaft 6 and in suitable ball bearing assemblies 22 and 23 are three ratchet wheels 24, 25 and 26 which are keyed at 35 to the shaft 21 so as to be rotated jointly in either direction by action of rocker frame and pawls 8 and 9. The center wheel 25 is provided with teeth that are uniformly inclined in either direction to receive a detent 27 carried by a leaf spring 28 secured to the motor bracket at 29.

15 Thus when the solenoid 1 is energized by the throwing of a suitable switch 30 into engagement with a contact 32 the armature 3 attracts the member 34 causing the frame 7 to rock to the right and hence the pawl 8 will enter into engagement with the teeth of sprocket wheel 26. The pawl 8 is normally out of engagement with the anti-clockwise and inclined peripheral teeth of wheel 26 by action of a compression spring 36 and against the stop 37. The pawl 8 may assume angular positions during advancing engagement; these angular positions are resiliently compensated by the spring 36. The pawl 8 thus being in engagement with ratchet wheel 24 moves the latter one notch or more in a clockwise direction. The spring detent 27, engages the corresponding next tooth of detent wheel 25 to hold the latter and the wheel assembly and consequently the shaft 21 in this advanced position, until a repeated action occurs.

20 25 Likewise when switch 30 is thrown to engage contact 31 to energize solenoid 2 the armature 4 attracts the magnetic member 17 to move rocker frame 7 about its pivot 6 in a counterclockwise direction against the action of a tension spring 12 secured to the spacer bar 13 and to an extension 14 of the rocker frame 7. As a result of this rocking of the frame 7, the pawl 9, which is normally out of engagement with ratchet wheel 24 and at rest against its stop, is brought into engagement with the clockwise inclined teeth of

the ratchet. When the pawl 8 is in engagement with the teeth of wheel 24 the latter is then advanced one notch or more in a counterclockwise direction together with the wheel 25 and with respect to the detent 27, 28. Consequently there is a corresponding rotation of the shaft 21.

The foregoing detail description has dealt with the separate and selective energization of the two armatures and the alternate rotation of the ratchet wheel assembly and shaft 21 the distance of one notch or more either clockwise or counterclockwise. It is to be understood that this constitutes only one part of the invention, as it is proposed to have such rotation continue as long as the switch 30 engages either contact 31 or 32, and at a predetermined rate. In order to accomplish this there is provided a clock mechanism generally illustrated at 40 which is electrically included in circuit with switch 30 and a suitable electrical source 41 and ground 42. The clock, or timing device, may have a spring operated mechanism therein, or any desired prime mover, and may be adjusted as desired by a hand knob 43 for speed control of movement of an arm 46 carried on a shaft 47 driven by the timing device. The timing device is further provided with a plurality, such as fifty more or less, of spaced contacts 44 of uniform dimensions with equally spaced gaps 45 therebetween. Thus when the arm 46 is in engagement with one of the contacts 44 and switch 30 is engaging contact 31 the circuit is complete and solenoid 2 is energized. As previously explained, this causes a movement of the wheel assembly and the shaft 21 the distance of one notch or more counterclockwise. As soon as brush 46 is driven out of engagement with one of the contacts 44 over the adjacent gap 45 the solenoid immediately becomes deenergized and the pawl 8 is released from its engagement with ratchet wheel 24 and assumes the normal neutral position shown in Figure 1 with the detent 27, 28 engaging wheel 25 to hold the assembly in the advanced position. Further movement of brush 46 brings it into engagement with another one of the contacts 44 which automatically closes the circuit to bring about a reenergization of the same solenoid 2 and the cycle of engagement of pawl 8 with ratchet wheel 24 to advance the latter and shaft 21 in a counterclockwise direction is repeated; and intermittently thus repeated as long as switch 30 is maintained in contact with contact 31. It follows, in the light of the foregoing description, that upon the throwing of switch 30 into engagement 32 the alternate automatic engagement and disengagement of brush 46 with contacts 44 of the timing device similarly energizes solenoid 1 to rock the lever 7 clockwise and then deenergize the solenoid permitting spring 18 to return it to normal and causing the pawl 8 to intermittently advance the wheel 26 and shaft 21 in a clockwise direction. Shaft 21 has fixed thereon a bevel gear 48 to mesh with a similar gear 49 mounted on a shaft 50 which may extend to actuate the mechanism of a conventional directional gyro box for an automatic pilot.

From the foregoing it will be seen that there has been provided a simple and convenient expedient whereby in an automatic pilot the desired rate of turn in either direction may be selected, predetermined and set and automatically maintained in either direction upon the operation of a simple switch means.

We claim:

1. In combination with an aircraft and an

automatic pilot therefor employing a directional gyro assembly and a device for rudder control and turn of the aircraft, a prime mover for said assembly including a rotatable shaft, means for controlling the speed of rotation of said shaft in either direction, said means comprising a pair of independently and selectively electrically energizable devices for advancing said shaft in step by step rotation in either selected direction, an adjustable timing device for automatically and alternately energizing and deenergizing the selected one of said electrical devices, and switch means between said timing device and said electrical source of power, whereby said shaft is automatically rotated at a constant speed predeterminedly selected and set up in said timing device and continuously rotated in the desired direction predeterminedly selected and set up in said switch means until said switch means is thrown to a neutral or opposite control position.

2. In combination with an aircraft and an automatic pilot therefor employing a directional gyro assembly and a device for rudder control and turn of the aircraft, a prime mover for said assembly including a rotatable shaft, means for controlling the speed of rotation of said shaft in either direction, said means comprising a source of electric power, a pair of independent solenoids and switch means for selectively energizing one or the other, pawl and ratchet means operable by each of said solenoids for rotating said shaft in opposite directions in step by step movement according to which solenoid is selectively energized and a timing device that is adjustable as to speed of rotation and in circuit with said switch and adapted, upon operation of the latter to selectively energize one or the other solenoid, whereby said shaft is automatically rotated at a constant speed predeterminedly selected and set up in said timing device and continuously rotated in the desired direction predeterminedly selected and set up in said switch means until said switch means is thrown to a neutral or opposite control position.

3. In combination with an aircraft and an automatic pilot therefor employing a directional gyro assembly and a device for rudder control and turn of the aircraft, a prime mover for said assembly including a rotatable shaft, means for controlling the speed of rotation of said shaft in either direction, said means comprising a source of electric power, a pair of independent solenoids and switch means for selectively energizing one or the other, pawl and ratchet means operable by each of said solenoids for rotating said shaft in opposite directions in step by step movement according to which solenoid is selectively energized and a timing device that is adjustable as to speed of rotation and in circuit with said switch and adapted, upon operation of the latter to selectively energize one or the other solenoid, whereby said shaft is automatically rotated at a constant speed predeterminedly selected and set up in said timing device and continuously rotated in the desired direction predeterminedly selected and set up in said switch means until said switch means is thrown to a neutral or opposite control position.

4. In combination with an aircraft and an automatic pilot therefor employing a directional gyro assembly and a device for rudder control and turn of the aircraft, a prime mover for said assembly including a rotatable shaft, means for controlling the speed of rotation of said shaft in

either direction, said means comprising a source of electric power, a pair of independent solenoids and switch means for selectively energizing one or the other, pawl and ratchet means operable by each of said solenoids for rotating said shaft in opposite directions in step by step movement according to which solenoid is selectively energized and a timing device that is adjustable as to speed of rotation and in circuit with said switch and adapted, upon operation of the latter to selectively energize one or the other solenoid, said timing device including a plurality of spaced contacts separated by gaps and a brush driven by the clockwork of said timing device whereby said brush when in contact with one of said contacts completes the circuit from said source to said switch and to the selected solenoid to energize the latter and cause the deenergization of the latter when in alignment with one of said gaps and out of engagement with any of said contacts, whereby said shaft is automatically rotated at a constant speed predeterminedly selected and set up in said timing device and continuously rotated in the desired direction predeterminedly selected and set up in said switch means until said switch means is thrown to a neutral or opposite control position.

5. In combination with an aircraft and an automatic pilot therefor employing a directional gyro assembly and a device for rudder control and turn of the aircraft, a prime mover for said assembly including a rotatable shaft, means for controlling the speed of rotation of said shaft in either direction, said means comprising a source of electric power, a pair of independent solenoids and switch means for selectively energizing one or the other, pawl and ratchet means operable by each of said solenoids for rotating said shaft in opposite directions in step by step movement according to which solenoid is selectively energized and a timing device that is adjustable as to speed of rotation and in circuit with said switch and adapted, upon operation of the latter to selectively energize one or the other solenoid, said timing device including a plurality of spaced contacts separated by gaps and a brush driven by said timing device whereby said brush when in contact with one of said contacts completes the circuit from said source to said switch and to the selected solenoid to energize the latter and cause the deenergization of the latter when in alignment with one of said gaps and out of engagement with any of said contacts and a spring operated detent for maintaining said shaft in each advanced rotative position, whereby said shaft is automatically rotated at a constant speed predeterminedly selected and set up in said timing device and continuously rotated in the desired direction predeterminedly selected and set up in said switch means until said switch means is thrown to a neutral or opposite control position.

6. Means for controlling the speed of rotation of a shaft in either direction, said means comprising a source of electric power, a pair of independent solenoids and switch means for selectively energizing one or the other, pawl and ratchet means operable by each of said solenoids for rotating said shaft in opposite directions in step by step movement according to which solenoid is selectively energized and a timing device that is adjustable as to speed of rotation and in circuit with said switch and adapted, upon operation of the latter to selectively energize one or the other solenoid, to automatically control the

10 speed of rotation of said shaft in the corresponding selected direction of rotation, said pawl and ratchet means comprising three ratchet wheels keyed to rotate with said shaft, the middle wheel having uniformly inclined peripheral teeth to receive a spring detent and the outer two wheels having oppositely and downwardly inclined peripheral teeth to be separately and independently engaged with and disengaged from its corresponding adjacent pawl, said pawls being carried by a rocker arm adjacent either end thereof and resiliently urged inwardly against a stop but normally out of engagement with either ratchet wheel, spring means for normally maintaining said rocker arm in neutral level position, contacts carried by said rocker arm and adapted to be attracted by either solenoid when the latter is energized so as to rock said rocker arm and force the pawl on the opposite end of said rocker arm upwardly into operative engagement with its corresponding ratchet wheel.

7. Means for controlling the speed of rotation of a shaft in either direction, said means comprising a source of electric power, a pair of independent solenoids and switch means for selectively energizing one or the other, pawl and ratchet means operable by each of said solenoids for rotating said shaft in opposite directions in step by step movement according to which solenoid is selectively energized and a timing device that is adjustable as to speed of rotation and in circuit with said switch and adapted, upon rotation of the latter to selectively energize one or the other solenoid, to automatically control the speed of rotation of said shaft in the corresponding selected direction of rotation and a spring operated detent for maintaining said shaft in each advanced rotative position, said pawl and ratchet means comprising three ratchet wheels 30 keyed to rotate with said shaft, the middle wheel having uniformly inclined peripheral teeth to receive a spring detent and the outer two wheels having oppositely and downwardly inclined peripheral teeth to be separately and independently engaged with and disengaged from its corresponding adjacent pawl, said pawls being carried by a rocker arm adjacent either end thereof and resiliently urged inwardly against a stop but normally out of engagement with either ratchet wheel, spring means for normally maintaining said rocker arm in neutral level position, contacts carried by said rocker arm and adapted to be attracted by either solenoid when the latter is energized so as to rock said rocker arm and force the pawl on the opposite end of said rocker arm upwardly into operative engagement with its corresponding ratchet wheel.

8. In combination with an aircraft and an automatic pilot therefor employing a directional gyro assembly and a device for rudder control and turn of the aircraft, a prime mover for said assembly including a rotatable shaft, means for controlling the speed of rotation of said shaft in either direction, said means comprising a source of electric power, a pair of independent solenoids and switch means for selectively energizing one or the other, pawl and ratchet means operable by each of said solenoids for rotating said shaft in opposite directions in step by step movement according to which solenoid is selectively energized and a timing device that is adjustable as to speed of rotation and in circuit with said switch and adapted, upon operation of the latter to selectively energize one or the other solenoid,

a spring operated detent for maintaining said shaft in each advanced rotative position, said pawl and ratchet means comprising three ratchet wheels keyed to rotate with said shaft, the middle wheel having uniformly inclined peripheral teeth to receive a spring detent and the outer two wheels having oppositely and downwardly inclined peripheral teeth to be separately and independently engaged with and disengaged from its corresponding adjacent pawl, whereby said shaft is automatically rotated at a constant speed predeterminedly selected and set up in said timing device and continuously rotated in the desired direction predeterminedly selected and set up in said switch means until said switch means is thrown to a neutral or opposite control position.

9. In combination with an aircraft and an automatic pilot therefor employing a directional gyro assembly and a device for rudder control and turn of the aircraft, a prime mover for said assembly including a rotatable shaft, means for controlling the speed of rotation of said shaft in either direction, said means comprising a source of electric power, a pair of independent solenoids and switch means for selectively energizing one or the other, pawl and ratchet means operable by each of said solenoids for rotating said shaft in opposite directions in step by step movement according to which solenoid is selectively energized and a timing device that is adjustable as to speed of rotation and in circuit with said switch and adapted, upon operation of the latter to selectively energize one or the other solenoid, to automatically control the speed of rotation of

said shaft in the corresponding selected direction of rotation, said timing device including a plurality of spaced contacts separated by gaps and a brush driven by said timing device whereby said brush when in contact with one of said contacts completes the circuit from said source to said switch and to the selected solenoid to energize the latter and cause the deenergization of the latter when in alignment with one of said gaps and out of engagement with any of said contacts and a spring operated detent for maintaining said shaft in each advanced rotative position, said pawl and ratchet means comprising three ratchet wheels keyed to rotate with said shaft, the middle wheel having uniformly inclined peripheral teeth to receive a spring detent and the outer two wheels having oppositely and downwardly inclined peripheral teeth to be separately and independently engaged with and disengaged from its corresponding adjacent pawl, said pawls being carried by a rocker arm adjacent either end thereof and resiliently urged inwardly against a stop but normally out of engagement with either ratchet wheel, spring means for normally maintaining said rocker arm in neutral level position, contacts carried by said rocker arm and adapted to be attracted by either solenoid when the latter is energized so as to rock said rocker arm and force the pawl on the opposite end of said rocker arm upwardly into operative engagement with its corresponding ratchet wheel.
